UNITED STATES PATENT OFFICE.

OLIVER COLEMAN, OF WAWANESA, MANITOBA, CANADA.

TELEPHONE SYSTEM.

1,109,111.

Specification of Letters Patent. Patented Sept. 1, 1914.

Application filed April 8, 1912. Serial No. 689,319.

To all whom it may concern:

Be it known that I, OLIVER COLEMAN, of the village of Wawanesa, in the Province of Manitoba, Canada, have invented certain new and useful Improvements in Telephone Systems, of which the following is the specification.

The invention relates to a rural telephone system or a party line system, and the object 10 of the invention is to provide a device of the above class wherein all telephones on the line can be rung selectively so that when one party telephones or calls another only the party called is signaled, and further to 15 provide a telephone system wherein the conversation carried on can only be heard by those for whom it is intended and not by other subscribers.

With this and other objects in view which 20 will be more apparent as the description proceeds the invention consists in the novel arrangement and construction of parts herein-after more particularly described and later pointed out in the appended claims.

25 Figure 1 represents diagrammatically the line wires and the parts as they are connected electrically at one station or subscriber's house. Fig. 2 represents an enlarged front elevation of the dial and adjoining parts. Fig. 3 is a side view of the parts appearing in Fig. 2. Fig. 4 is a plan view of the key. Fig. 5 is a rear view of the dial and cam groove carried thereby. Fig. 6 is a side view of the central portion 30 of the tube and suspending stirrup. Fig. 7 is a vertical sectional view through the central portion of the tube and stirrup showing the valve within the tube. Fig. 8 is a plan view of the base piece and the parts carried thereby. Fig. 9 is a plan view of the 35 contact pieces engaged by the tube.

In the drawings like characters of reference indicate corresponding parts in each figure.

45 At the outset I may say that I do not desire to restrict myself in any way whatever to the particular manner in which the parts shortly described are arranged or supported in relation to each other as this is 50 simply a matter of convenience and does not in any way involve invention. I have shown certain parts located within the box but the box is simply employed as a support and protection in this instance. It is also 55 to be understood that various other simultaneous telegraphic and telephonic circuits

can be used to advantage, that which has been introduced in the present drawings being known as Cail-ho's method wherein the two line wires that form one complete metallic telephone circuit are connected in parallel for one side of the telegraph circuit, the ground being used as the other side of the telegraph circuits.

1 represents a box in which I have located a stand 2 provided with a device 3 very similar to what is known as the Bunnell sounder. The device comprises electric magnets 4 wound in the usual way and connected with binding posts 5 and 6.

65 7 is a standard carried by the stand and provided with trunnion screws 7' which support a lever 7² carrying an armature 8, which armature is directly opposite the cores 9 of the electro-magnet. A compression spring 10 bears on the short end of the lever and holds the armature normally in its upper position. An adjustable screw 11 controls the upper position of the long 70 end of the lever, which screw is carried by 75 the anvil 12 located on the stand.

13 and 14 are plates or standards firmly secured to the stand 2 and providing bearings for a spindle or shaft 15 which is supplied with a ratchet wheel 16 fixed on the 80 shaft.

85 The long end of the lever is provided with an extending dog 17 which is adapted to engage with the teeth of the ratchet wheel at one side, while the stand supports 90 a further spring dog 18 which engages with the teeth on the other side of the ratchet wheel. The dog 17 is designed to turn the ratchet wheel one ratchet tooth each time it is depressed, while the dog 18 95 prevents retrograde motion.

95 The spindle 15 is fitted with a dial 19 which turns with it and is supplied with a number of concentrically arranged openings 20 which are arranged to receive the 100 inturned end 21' of a projecting arm 21 carried by a disk 22 slidable on the shaft and spaced from the dial by a sleeve 23. The disk is fitted with a finger piece 24 and is held normally against the sleeve by a 105 pressure spring 25 slipped on the spindle and bearing at its outer end against the knob 26.

110 The openings 20 are numbered consecutively from 1 to 10 in the present instance, there being further openings notated by the letters "C" and "N". At the outer edge

of the dial I have placed further numbers 1 to 10 inclusive and further letters "C" and "N" which are arranged in a definite relation to the numbers notating the openings 5 (20). It is to be noticed that the corresponding numbers and letters on the inner and outer circles are at opposite sides of the center of the dial, that is to say for example, the opening notated by the number 5 on the 10 inner circle is diametrically opposite the number 5 on the outer circle. The reason for this will be apparent hereafter.

27 is a bar suspended from the top of the box and provided at its lower end with a 15 pivoted catch piece 28 bearing normally on the upper edge of the disk and arranged to hold the disk against movement outwardly on the spindle.

29 is a releasing plate fixed on the outer 20 face of the dial and arranged to engage with and depress the rear end of the catch piece, thereby raising the forward end from the disk and allowing the same to be moved outwardly on the spindle by the operator.

25 Above the device 3 and suspended by a hanger 30 from the box is a contact tube 31, which tube has the ends closed and is supported centrally from a stirrup 32 located at the lower end of the hanger.

30 33 is a valve located within the tube and carried by a valve stem 34 which passes through the tube and is pivotally mounted in the stirrup. A strap or band 35 encircles this tube and supports also the valve stem.

35 The above construction is arranged so that the tube can be swung in respect to the stirrup and the valve independently turned within the tube. The forward end of the tube is supplied with a pin 36 which enters a 40 cam groove 37 appearing on the back face of the dial. The cam groove is of an irregular circular shape, having a portion thereof 37' concentric to the spindle and the remaining portion thereof 37² passing away from the 45 spindle but continuous. The portion 37² is offset at 37³, which offset appears in each dial directly behind the number indicating the number on the telephone. In the present instance the drawing shows this position 50 for central. This allows the forward end of the tube to be swung upwardly at this point if desired. Mercury or alcohol is placed in the tube so as to be free to flow from the end of the same upon the tube 55 being turned in the horizontal position and the position of the tube is controlled by the pin operating in the cam groove. The arrangement is such that the liquid is in the forward end of the tube, that is, adjoining the dial, when the pin is in the portion 37' of the cam groove. As the dial is turned and the pin travels into the portion 37² of the groove the forward end of the tube is 60 constantly raised until the pin reaches the 65 position indicated by the letter "P" (see

Fig. 5) at which point the forward end of the tube is elevated above the central portion thereof. This causes the liquid contained therein to flow gradually to the rear end of the tube thereby causing the tube to close an electric circuit later referred to. The pin at this time swings across the offset 37³ and engages with the outer side of the cam groove.

38 are two guides extending upwardly 75 from the standard 14 and receiving the forward end of the tube, thereby guarding the same against lateral displacement. The valve 33 is supplied so that the flow of liquid within the tube can be controlled.

In Fig. 4 I have shown a "Morse" telegraph key of well known construction, which I will describe in detail for the sake of clearness. A steel lever 75 having button 46 is pivoted at 76. Metal legs 77, 77 project through the supporting table and are supplied with wing nuts 78 for clamping purposes. The right leg is connected directly to the metal base 79; the left leg passes through the base and is insulated therefrom by a hard rubber bushing 80. On its top there is a cone-shaped cap 81 termed the anvil carrying a small platinum contact point 82. A small strip of metal 83 extends out from the cap. At a point on its under 90 side directly above the contact 82 the lever 75 is supplied with a platinum contact 84 termed the hammer. A curved strip of metal 85 termed the circuit breaker is pivoted on the base 79. When the circuit closer 100 is pushed under the strip 83 projecting from the cap 81 it closes the circuit through the wires f (hereinafter mentioned) regardless of the opening between the anvil and the hammer. The lever 75 and the circuit closer 105 are supplied with hard rubber finger tips by which they may be handled freely without danger of shock. A spring 85' adjustable by a set screw 86 normally holds the lever 75 from the anvil. When the operator is 110 about "to send" the circuit closer must first be pushed out from under strip 83 so that the lever when operated may open and close the circuit, it being readily seen that when the hammer is pushed down into contact 115 with the anvil the circuit is closed at that point as will be better understood as the description proceeds.

43 represents the transmitter of a telephone, 44 the receiver of a telephone, and 46' the telephone bell.

47 represents the induction coil of the telephone comprising a primary and secondary coil as shown and 48 represents the telephone battery, while 49 is the bell battery.

50 is a contact member supplied with contact pieces 51 and 52 connected directly to the binding posts 53 and 53' and having the contact tip 51 located beneath the free end 130

of the tube so that it is engaged and carried down by the tube when the tube swings thereby making contact with the contact piece 52.

5 54 is a base piece carrying spring contact pieces 55, 56, and 57, connected with binding posts 58, 59, and 60, the contact pieces 56 and 57 being normally in engagement, while that of 55 is arranged to make contact 10 with the piece 57 when it is depressed by the arm 21, it being noticed that the arm is supplied with an offset pin 21² at the free end. The contact piece 57 is considerably wider than the contact piece 56 to allow the arm 15 to turn freely and depress the member 57 without moving the member 56.

“a” and “b” are line wires passing from place to place, which line wires are used for transmitting both telegraphic and telephonic 20 currents. The contact pieces 56 and 57 are interposed in the line wire “a” as shown the line wire being attached to the binding posts 59 and 60.

A wire “c” leads from the receiver arm 25 to the binding post 53' and a further wire “d” extends from the binding post 53 to the receiver arm contact and is arranged so that the receiver arm makes contact with it when the receiver is on the arm, it being 30 understood that the receiver arm rises in the ordinary way as soon as the receiver is removed, thereby breaking circuit through the wire “c”. The battery 49 and the bell 46' are located in this latter circuit.

35 The transmitter 43, the battery 48, the induction coil 47, the receiver 44, and the arm 45 are arranged in the usual relation with each other, and a wire “e” passes from the receiver to the binding post 58 already referred to.

40 A ground wire “f” passes to one of the binding posts 42 of the key, then continues from the other post and is connected to the binding post 5 of the device 3. It then 45 passes from the binding post 6 to the point “F” where it divides and is connected to two identical windings “D” and “E” of insulated copper wire, each having exactly the same resistance and the same number of 50 turns, which turns are each wound around soft iron cores. The windings “D” and “E” are fastened to the line wires “a” and “b”, respectively. A wire “g” connects the line wire “b” with the wire “c”.

55 61 is a battery located in the telegraphic circuit. The telegraphic current passes through the wire “f” to the point “F” provided the key 39 is closed and then divides and passes through the two windings “D” 60 and “E” in opposite directions so that the two coils tend to magnetize the iron cores equally in an opposite direction and consequently the self induction is practically zero and the impedance to the telegraph circuit 65 is no larger than the resistance. The return

circuit is completed through the ground, it being understood that the current passes through similar coils and a wire corresponding to that “f” at the other end of the line. With the telephonic currents however the 70 case is entirely different as the current would be made to pass through the coils “D” and “E” in the same direction so that the impedance offered by the coils to the telephonic current is very large. Therefore practically 75 all the current is forced through the telephone where it belongs provided of course that the contacts 55 and 57 are touching and the receiver is off the hook.

80 From the above it will be seen that the coils prevent the telephone currents from passing through them but as they only add one half the resistance of one coil to the telegraphic circuit (since the two coils are in parallel) they do not interfere appreciably 85 with the telegraphic signals.

I will now describe how the system is used assuming that I, subscriber No. 10, desire to call and talk to subscriber No. 4. At this point it may be well to explain that the 90 outer numbers on the dial refer to the call numbers of the subscribers on the line, each subscriber having a definite number such as just suggested, and further it is to be understood that the arm 21 in each particular instance is secured to the disk in a position which will allow the extending end 21' thereof to pass into the opening on the inner circle representing the call number in each 95 case of the respective subscribers. When I 100 (No. 10) desire to call subscriber No. 4 I withdraw the end 21' of the arm from the opening 10 of the inner circle on the dial and turn the arm around until it comes directly opposite the called number 4 on the 105 inner circle of the dial when it is allowed to pass into this opening. I then open and close the telegraphic circuit by operating the key 39 which causes all the dials on the line to turn due to the action of the dog 17 which is raised and lowered by the action of the 110 electro-magnet on the armatures 8. This is continued until call No. 4 on the outer circle of my dial is up. I then know that the arm 21 of the telephone attachment of subscriber 115 No. 4, the party called, is down. The bell 46' at the called end of the line is then rung for the reason that the cam groove on his dial has the offset portion 37³ thereof up with the result that the tube has been swung 120 to a position which makes the connection between the contacts 52 and 51 and thereby closing the circuit containing the bell 46'. It is here remarked that each subscriber 125 leaves his arm 21 when not using the line diametrically opposite the offset portion 37³ of the cam groove, that is, in the hole indicating his number. This explains why I know that the called arm is down at his end 130 of the line as above described. No other

telephone bell except subscriber's No. 4 will ring for no other dial is in a position which will free the pin 36 to swing upwardly and consequently allow the glass tube to press together the contacts 51 and 52. Subscriber No. 4 hearing the bell ring answers the telephone and takes down the receiver thereby closing the telephone circuit as the contacts 55 and 57 are in engagement at both ends of the line. Immediately the transmitter is raised from the hook the bell stops ringing as this breaks the bell circuit. When the conversation is completed the party calling returns his dial by means of the telegraphic current and switch 39 back to the original position termed "not-in-use position," which position is when the dial has the letter "N" on the outer circle next to the top and consequently the opening represented by the letter "N" on the inner circle next to the bottom or down. Adjoining the "not-in-use position" (that is letter "N") I have placed two letters "C" adjoining openings on the dial on the inner and outer circle, which letters "C" are diametrically opposite each other and indicate central. One can call central in the same manner as just described for calling No. 4 if it is desired to get a through connection to any other similar system.

The catch piece 28 serves as a means for preventing anyone along the line from shifting their disk except when the catch piece is raised clear of the disk by the plate 29. This can only happen when the disk is in a position at either "not-in-use" and "central" as indicated on the outer circle of the dial in the respective cases and will be readily understood.

It will be understood that the dials will all rotate and the cams all turn, but it is pointed out that no tube 31 will swing down and close its circuit until the party calling actually stops manipulating his key. It will also be noticed that the mercury or other such liquid in each tube is controlled by the valve 33 thereof so that the mercury flows from end to end of the tube slowly; slowly enough to allow the pins 36 to pass across the bases of the offsets 37³ (when the cams rotate) without swinging up in said offsets sufficiently far to allow the outer ends of the tubes to make contact between the contact pieces 51 and 52 of the local bell circuits. The contacts can only be engaged in the local bell circuit of the party called when the calling party actually stops operating his key as the tube of the party called is the only tube which can at this time swing up into the top of the offsets 37³. It has got to swing to the top before the circuit is closed in the local telephone of the party called.

What I claim as my invention is:—

1. In a telephone party line system, a telegraphic circuit means for opening and clos-

ing the telegraphic circuit, a normally open telephonic circuit, normally open bell circuits, rotatable dials located in the telegraphic circuit at each station in the system and controlled by the same, the dials presenting in each instance numbers representing all the call numbers of the parties in the system and means for rotating said dials a fixed distance for each make and break in the telegraphic circuit, disks arranged to be set in any relation to the respective dials, the disks, when set rotating with the dials, means actuated by the disks in rotating for closing the telephonic circuits at the respective stations, contact pieces introduced in the bell circuits and adjoining the dials, a cam groove formed on each dial, a tiltable member controlled by each cam groove and arranged when tilted, to engage the contact pieces in the bell circuits, as and for the purpose specified.

2. In a telephone party line system, a telegraphic circuit means for opening and closing the telegraphic circuit, a normally open telephonic circuit, normally open bell circuits, rotatable dials located in the telegraphic circuit at each station in the system and controlled by the same, the dials presenting in each instance numbers representing all the call numbers of the parties in the system and means causing said dials to rotate a fixed distance for each make and break in the telegraphic circuit, disks arranged to be set in any relation to the respective dials, the disks when set rotating with the dials, means actuated by the disks in rotating for closing the telephonic circuits at the respective stations, contact pieces introduced in the bell circuits and adjoining the dials, a cam groove formed on each dial, a pivoted member adjoining the dial having the forward end entering or controlled in its movement by the groove, and the rear end thereof adjoining the contact pieces aforesaid in each bell circuit, the arrangement being such that the contact pieces in any bell circuit are closed when the adjoining pivoted member is tilted by the cam groove to cause the rear end thereof to engage the adjoining contact members, as and for the purpose specified.

3. In a telephone party line system, a telegraphic circuit means for opening and closing the telegraphic circuit, a normally open telephonic circuit, normally open bell circuits, rotatable dials located in the telegraphic circuit at each station in the system and controlled by the same, the dials presenting in each instance numbers representing all the call numbers of the parties in the system and means causing said dials to rotate a fixed distance for each make and break in the telegraphic circuit, disks arranged to be set in any relation to the respective dials, the disks when set rotating with the dials, means actuated by the disks

in rotating for closing the telephonic circuits at the respective stations, contact pieces introduced in the bell circuits and adjoining the dials, a cam groove formed on each dial, a centrally pivoted hollow tube adjoining each dial having the forward end thereof extending into or controlled by the groove and the rear end thereof located above the contact pieces of each bell circuit and a liquid within the tube, the arrangement being such that the contact pieces in the respective bell circuits are engaged when depressed by the rear end of the adjoining tube, as and for the purpose specified.

4. The combination comprising a rotatably mounted spindle, electrically controlled means for rotating the spindle, a dial fixed on the spindle, a disk adjoining the dial and slidably on the spindle, a sleeve interposed between the dial and the disk, a spring normally holding the disk against the sleeve, an arm fixed to the disk and radiating therefrom, the arm having a portion thereof extending from the disk normally into one or other of the openings in the dial, a suitably supported catch piece adjoining the disk and normally preventing the same from being shifted on the spindle, and a trip piece fixed on the dial and engageable with the catch piece and designed to release the

same from the disk, as and for the purpose specified.

5. The combination comprising, a rotatable spindle, a dial secured to the spindle and rotatable therewith, electrically controlled means for rotating the spindle, a cam groove formed on the dial, a pivotally mounted tube adjoining the dial, said tube having the ends closed and being provided at the forward end with a pin passing into the cam groove and a liquid within the tube, as and for the purpose specified.

6. The combination comprising, a rotatable spindle, a dial secured to the spindle and rotatable therewith, electrically controlled means for rotating the spindle, a cam groove formed on the dial, a pivotally mounted tube adjoining the dial, said tube having the ends closed and being provided at the forward end with a pin passing into the cam groove, a liquid within the tube and an adjustable valve located within the tube designed to control the flow of the liquid through the tube, as and for the purpose specified.

Signed at Winnipeg, in the Province of Manitoba, this 15th day of March, 1912.

OLIVER COLEMAN.
